UNITED STATES PATENT OFFICE

CHARLES LEIGH SEBRING, OF SEBRING, OHIO, ASSIGNOR TO THE SEBRING POTTERY COMPANY, OF SEBRING, OHIO, A CORPORATION OF OHIO

DESIGN FOR A DISH

Application filed September 24, 1929. Serial No. 32,848. Term of patent 14 years.

To all whom it may concern:

Be it known that I, CHARLES L. SEBRING, a citizen of the United States, residing at Sebring, in the county of Mahoning and State of Ohio, have invented a new, original, and ornamental Design for Dishes, of which the following is a specification, reference being had to the accompanying drawing, forming part thereof.

I claim:

The ornamental design for a dish, substantially as shown.

In testimony whereof I have hereunto set my hand.

CHARLES LEIGH SEBRING.
